UNITED STATES PATENT OFFICE.

KENNETH BEEBE, OF PORTLAND, OREGON.

ANCHOR.

1,239,557.

Specification of Letters Patent. Patented Sept. 11, 1917.

Application filed April 13, 1914, Serial No. 831,397. Renewed March 23, 1917. Serial No. 156,968.

To all whom it may concern:

Be it known that I, KENNETH BEEBE, a citizen of the United States, residing at Portland, in the county of Multnomah and 5 State of Oregon, have invented certain new and useful Improvements in Anchors, of which the following is a specification.

My invention relates to an improvement in anchors, and it has for its object to provide 10 an anchor in which the shank is loosely secured in the anchor head, with novel means for securing the shank in place.

This object is accomplished by means of the structure shown in the accompanying 15 drawing, in which—

Figure 1 is a plan view of my improved anchor.

Fig. 2 is an end view of Fig. 1.

Fig. 3 is a bottom plan view of Fig. 1. 20 Fig 4 is a sectional view, taken on the line A—A of Fig. 1.

Fig. 5 is a plan view of a locking element.

Describing the drawing in detail, 1 represents the anchor head having the flukes 1^a 25 formed integrally thereon, and in the median line between said flukes is formed a transverse opening 5 into which is passed the shank 2.

At each side of the opening 5 is an enlargement 6 adapted to receive the retaining pin or trunnion 4 which is fixed transversely 30 in the end of the shank, to form a bearing therefor and upon which the shank is free to rock in the expanded portion 3 of its 35 opening between the sides of the anchor head.

In the body of the anchor, at the inner side the opening 6 is further enlarged to 40 form the circular recess 8, forming a shoulder, at diametrically opposed sides of which are formed the stops 12, one at the front and the other at the rear side of the opening 5.

Transversely of the opening 5 is formed 45 in the bottom of the anchor head a further opening 5^a whose longitudinal or side portions register with those of the corresponding sides of the stops 12 and whose end portions register with the outer limit of the 50 shoulder 8. As the shank is inserted into its opening 5 from the lower side of the head 1, the bearing pin 4 will be free to pass through the transverse enlargement 5^a into its seat 6.

55 On placing the shank in position, the trunnion will pass freely through the space or

opening 5^a, into the seat 6; whereupon the plate 7, which conforms to the opening 5^a, may be inserted through that opening onto the shoulder 8, where it will rest between 60 the stops 12. This plate may now be rotated upon the shoulder 8 until each end portion comes against the corresponding stop 12, where it will stand at right angles to its original position, and directly across 65 the aperture 5. The end portions will thus engage beneath the outer portion of the anchor head and thereby effectually close the aperture 5 and prevent possible dislodgment of the shank. 70

To prevent retrograde movement of the locking plate I have inserted a screw 11 through the outer casing of the anchor head so as to stand against the free edge of the plate, thereby rendering accidental releasing impossible. The plate may be rotated by means of a tool inserted through the opening 9. 75

The body of the anchor is provided in its upper face with a plurality of cavities, as 80 at 1^b, leaving an outer shell which may be irregularly shaped and provided with scalloped edges, as shown, or it may be formed in any suitable and convenient design. The purpose of the cavities is to form receptacles 85 into which the silt or muddy deposits into which the anchor is cast may collect and when covering the anchor, it will form with the surrounding deposit, a homogeneous mass, which will produce a strong 90 suction tending to hold the anchor in place.

The apertures 1^c leading from each of the recesses to the lower face of the anchor permits the mud to be washed from those recesses as the anchor is lifted from its moorings. 95

Having thus described my invention, what I claim as new and desire to obtain by Letters Patent, is—

1. An anchor comprising a head-piece 100 having a fluke at each end and a shank opening in the head-piece intermediate said flukes, a trunnion seat in each side of the shank opening leading to the bottom face of said head-piece, a recess formed in the 105 shank opening adjacent the lower outlet thereof, a shank having a trunnion at each side of one end adapted to be inserted from the lower side into said opening, and a plate adapted to pass within said trunnion seats 110 and to be rotated within said recess to lock the shank opening.

2. An anchor comprising a head-piece having a fluke at each end and a shank opening in the head-piece intermediate said flukes, a trunnion seat in each side of the shank opening leading to the bottom face of said head-piece, a recess formed in the shank opening adjacent the lower outlet thereof, a shank having a trunnion at each side of one end adapted to be inserted from the lower side into said opening, a plate adapted to pass within said trunnion seats and to be rotated within said recess to lock the shank opening, and means for securing the plate in fixed position.
- 15 3. An anchor comprising a head piece having a fluke at each end and a shank opening in the head piece between said flukes, said shank opening being larger in the under

side of said head piece than it is through the top side of said head piece, whereby to form 20 a chamber in said head piece, a shank provided at one end with an enlarged portion, said shank being adapted to be inserted upwardly through said head piece with its enlarged portion occupying the chamber therein, and a retaining member for closing the bottom of said chamber in said head piece, said retaining member being adapted to be locked in place in said chamber by being rotated a partial turn therein.

In testimony whereof I affix my signature in the presence of two witnesses.

KENNETH BEEBE.
